UNITED STATES PATENT OFFICE

FREDERICK W. HEISLER, OF SCHENECTADY, NEW YORK

SUPPORT FOR MIDDLE GUIDES OF LOCOMOTIVES

Application filed May 17, 1929. Serial No. 363,890.

This invention relates generally to means for supporting the crosshead guides located between the frames of locomotives, and more particularly to such locomotives when employing the lateral motion device described in U. S. Patent #1,565,781, or its equivalent.

The object of the invention is to provide, in an integral structure means for adjustably supporting a middle crosshead guide and the fulcrums or rock shafts of a lateral motion device of the class described in aforesaid patent, whereby said elements are incorporated in the locomotive structure in a stronger, lighter, and more efficient manner than heretofore possible.

The improvement claimed is hereinafter fully set forth.

In the accompanying drawings: Figure 1, is a side view, in elevation, of a portion of a locomotive comprising the device; Fig. 2, a rear view of the device as mounted on the locomotive; Fig. 3, a side view in elevation, of the device; Fig. 4, an enlarged plan view of the device; and Fig. 5, an end view, in elevation, of the same.

In the practice of the invention, referring descriptively to the specific embodiment thereof herein exemplified in Figs. 1 and 2, the integral structure 1, is mounted on the frames 2, of a locomotive comprising in addition to said frames 2, the power cylinder 3, in which is the piston rod 4, connected to the crosshead 5, which is operatively associated with the guide 6. The guide 6, thus positioned between the frames 2, 2, is supported at its forward portion 7, on suitable means attached to the cylinder 3, and its rearward portion is supported by the structure 1. Formed on the guide 6, is a suitable bolting flange 8, secured to the seat 9, formed on the structure 1, by means of the bolts 11, and has interposed therebetween the liners 10, through which latter means the adjustment and alignment of the guide 6, is effected.

The locomotive frames 2, 2, have also housed therein an axle 12, journalled in the boxes 13, 13, cooperating with the rocking levers 14 of the lateral motion device hereinbefore mentioned, said levers 14 being pivotally mounted on the rock shafts 15, 15,

which are seated in the fulcrum bosses 16, 16, formed integrally with the structure 1.

Referring now to Figs. 3 to 5 inclusive, it will be seen that the structure 1, comprises two pairs of feet, 17-18, 19-20, joined respectively by the substantially arched members 21, 22, and connected at their upper portions by the member 23, which also serves as a guide support, the seat 9, being formed thereon for that purpose. The feet 17-18, 19-20, are adapted to be firmly seated on the frames 2, 2, and are further provided with flanges 24, affording means for bolting them securely to said frames. The connecting members 21, 22, may be formed with any appropriate cross-section, and have incorporated with them the bosses 16, which serve for fulcrums or seats for the rock shafts 15 of the lateral motion device rockers 14, 14, which span the axle 12, and cooperate with the axle boxes 13.

It will at once be seen by those skilled in the art that the structure herein described effects a great saving in weight over the complex assembly formerly used, and that the permissible distribution of the metal in such a structure results in a stronger and more rapidly and easily positioned assembly than heretofore possible.

The invention claimed and desired to be secured by Letters Patent is:

1. A device for use in locomotives, comprising four supporting feet adapted for attachment to the side frames of the locomotive, means for supporting a middle guide thereon, and means for supporting a lateral motion device thereon.

2. In a locomotive, a support for a middle guide, comprising pairs of supporting members mounted on opposite frame members; means, including a guide support, joining the pairs of supporting members; and means whereby one of said pairs of supporting members support a lateral motion device.

3. In a locomotive, a support comprising, in an integral casting, pairs of members spanning an axle and adapted to have a lateral motion device mounted thereon, and means on said casting for adjustably supporting a crosshead guide.

4. In a locomotive, a support comprising

in an integral casting pairs of members mounted on opposite frame members and adapted to span an axle; means for supporting a lateral motion device; and a member joining the pairs of members, adapted to support a middle crosshead guide.

5. In a locomotive comprising frame members, a crosshead guide therebetween, and a driving axle having journal boxes mounted thereon, the combination of a guide support having two pairs of feet, each pair mounted on opposite frame members and adapted to span the axle; and bosses formed in each pair adapted to receive the rock shaft of a lateral motion device.

10. 6. In a locomotive comprising frame members having journal boxes for an axle mounted therein, and a crosshead guide therebetween, the combination of a support having 20 two pairs of feet mounted on opposite frame members; means, joining the feet, adapted to support the crosshead guide; and means associated with the feet, adapted to support a lateral motion device cooperating with the 25 journal boxes.

15. 7. In a locomotive, side frames; a support comprising four spaced members supported on the side frames providing thereby an open transverse space between same, and an open 30 longitudinal space between same; lateral motion devices disposed in the transverse space and secured to the support; and a guide extending into the longitudinal space and secured to the support.

35. FREDERICK W. HEISLER.
